AUTOMATIC VARIABLE PUMP

Merlyn M. Culver, Dayton, Ohio, assignor to
 United Aircraft Products, Inc., Dayton, Ohio, a
 corporation of Ohio

Application November 12, 1943, Serial No. 510,003

2 Claims. (Cl. 103—38)

This invention relates to pumps, and has particular reference to improvements in variable-stroke, variable-capacity pumps of the type comprising a cylinder, a rotor rotatable therein and provided with radial or transverse displacement chambers, pistons in said displacement chambers rotatable with said rotor, and means whereby said pistons are reciprocable in said chambers in response to their rotation with said rotor to accomplish their pumping function.

In many instances it is very desirable to employ a pump the output of which may readily be varied to maintain the fluid being pumped under constant or substantially constant pressure despite variations in the demand upon the pump and without dependence upon sudden and more or less widely varying changes in the speed of operation of the pump. For example, in the internal combustion engine art in general and particularly in the aircraft art, it is very desirable to employ an engine fuel pump which will deliver fuel to the engine under constant or substantially constant pressure and in accordance with more or less sudden and more or less widely varying changes in the speed of the engine, to variations in the load thereon, or to other causes.

Accordingly, one special and important object of the present invention is to provide a pump of the type mentioned, especially for use as a fuel pump for internal combustion engines in general and particularly for aircraft engines, but, of course, capable of various other uses, which is operable in response to variations in the pressure of the fluid being pumped rather than to variations in its speed of operation, to vary the stroke of its pistons and thereby vary its output, thus automatically to vary its delivery of fluid in accordance with variations in the demand therefor and to maintain the delivered fluid under constant or substantially constant pressure.

Another special and important object of the invention is to provide a pump of the character mentioned which, in general, is of simple, practical construction and which embodies simple, practical means for varying the stroke of its pistons in response to variations in the pressure of the fluid being pumped.

Another special and important object of the invention is to provide a pump of the character mentioned which is reversible and which includes by-pass means whereby fluid may be pumped or

otherwise circulated therethrough between the inlet and the outlet thereof when the same is idle.

Another special and important object of the invention is to provide a pump of the character mentioned embodying simple means to seal the same effectively against leakage of fluid therefrom.

Another special and important object of the invention is to provide a pump of the character mentioned which is strong, rugged and thoroughly reliable and efficient in operation.

With the foregoing and other objects in view, the invention consists in a pump of the character mentioned embodying the various novel features of construction, combination and arrangement of parts as will be hereinafter more fully described, illustrated in the accompanying drawings and defined in the appended claims.

In the accompanying drawings, wherein like characters of reference denote corresponding parts in the different views:

Fig. 1 is a side elevation of a pump constructed in accordance with one practical embodiment of the invention.

Fig. 2 is a diagrammatic view illustrating the pump embodied in a fuel feeding system of an aircraft engine.

Fig. 3 is a top plan view of the pump.

Fig. 4 is a central, vertical, longitudinal section through the pump showing the pressure responsive means positioned to cause full stroke reciprocation of the pump pistons.

Fig. 5 is a view similar to Fig. 4 showing the pressure responsive means positioned to render the pump pistons inoperable.

Fig. 6 is a cross section on the line 6—6 of Fig. 5.

Fig. 7 is a view looking toward the inner end of the plug unit for closing the outer end of the pump cylinder.

Fig. 8 is a central, vertical, transverse section through the pump with the pressure responsive means for varying the stroke of the pistons positioned as shown in Fig. 4.

Fig. 9 is a perspective view of the rotor and piston elements of the pump shown in separated relationship to each other; and

Fig. 10 is a perspective view of the closure cap unit illustrated in Fig. 7 with the parts thereof shown in separated relationship to each other.

Referring to the drawings in detail, it will be observed that the present pump comprises a casting, designated generally as 10, having therein a cylindrical chamber, designated as 11, and provided at opposite sides thereof with openings 12 and 13 communicating with opposite sides of said

chamber, respectively, and either of which may be for the inlet of fluid to the pump and the other for the outlet of fluid therefrom.

At what may be termed its inner and its outer ends, the cylinder 11 is closed by what may be termed plug units 14 and 15, respectively, which are duplicates of one another except as regards the main element of each of them, which main elements merely are specifically different from each other to adapt the units for convenient and practical mounting in the respective ends of said cylinder. In other words, each of said plug units includes a main element in the form of a relatively thick, circular plate 16 fitted snugly in the cylinder 11, and whereas this plate of the unit 15 includes a flange 17 to overlie and to be bolted against the outer end wall of the cylinder 10 to secure said unit 15 firmly in place in closing relationship to the outer end of the cylinder 11, the corresponding plate of the unit 14 is disposed entirely within the cylinder 11 and, therefore, is devoid of any such flange. In other respects the units 14, 15 are, in all essential respects and to all essential intents and purposes, reversed duplicates, or substantially reversed duplicates, of each other, the unit 14 being secured firmly in place in closing relationship to the inner end of the cylinder 10 by reason of the plate 16 thereof being disposed against an inwardly extending, annular, flange-like wall 18 of the casing 10 and by being fastened against said wall by bolts or screws 19.

Each plug unit 14, 15 includes a block 20 securely fastened by means of screws 20' or in any other suitable manner against the inner face of its related plate 16 and having in the face thereof adjacent to its related plate 16 a channel 21 extending from top to bottom thereof. Thus, in each plug unit 14, 15, between the plate 16 and the block 20, is provided a guide channel extending from top to bottom of the unit.

Slidably mounted in each guide channel 21 for vertical movement is a slide-piece 22, and projecting laterally inward from each slide piece through an opening 23 in the wall of the related block 20 defining the inner side of the channel 21 and inwardly beyond said wall, is a circular boss 24 on which is rotatably mounted a flat circular band 25. The openings 23 are of greater dimensions vertically than the diameters of the bands 25 to permit vertical movements of the slide-pieces 22 and of the bosses 24 with the bands 25 thereon relative to the blocks 20.

Coaxial with the cylinder 11 is a shaft 26 which extends through openings 27 in the slide-pieces 22 and the bosses 24 and which is journaled for rotation in central bearings in the plates 16. Carried by this shaft is the pump rotor, designated generally as 28. This rotor is of cylindrical form, fits the cylinder 11 fluid-tightly and at its ends abuts fluid-tightly against the inner faces of the blocks 20. In said rotor is a pair of slots 29 and 30 which extend from end to end and diametrically from side to side thereof at right angles to each other and which constitute displacement chambers in which the pump pistons, designated as 31, operate. The segmental portions of the rotor, formed by the slots 29, 30 therein, are connected together by a central web or hub 32 having a central opening through which the shaft 26 extends, and said rotor is suitably fastened to said shaft for rotation therewith as, for example, by means of a pin 32' extending transversely through aligned holes in said hub and said shaft.

The pump pistons 31 are of the same length as the rotor 28 and of the same width as the slots or displacement chambers 29, 30 so as to engage fluid-tightly at their sides with the walls defining the sides of said slots or displacement chambers and at their ends with the inner faces of the blocks 20, and are of lesser depth than said slots or displacement chambers 29, 30 so as to be reciprocable therein, their outer faces preferably being curved transversely on the same radius as the cylinder 11 and the rotor 28. These pistons are connected together in two opposite pairs, each pair by a web 33 located adjacent to one end of the pair so as to clear the web or hub 32 of the rotor 28, and the two pairs are disposed in the slots or displacement chambers 29, 30 in right angular relationship to each other with the pistons of each pair occupying positions diametrically opposite of said slots or displacement chambers, the webs 33 of the respective pairs being disposed at opposite sides of the web or hub 32 of the rotor 28. In the webs 33 are openings 34 through which the shaft 26 extends and which are amply long so that said shaft does not interfere with reciprocation of the pistons. Obviously, when the rotor 28 rotates, the pistons 31 rotate therewith.

At their ends, the pistons of each pair straddle the bands 25 and contact with the peripheries thereof, the distance between the band contacting inner face portions 35 of each pair of pistons being equal to the diameters of said bands which are equal in diameter to each other. Accordingly, if the slide-pieces 22 are adjusted to dispose the bosses 24 and the bands 25 eccentrically with respect to the shaft 26 and the rotor 28, rotation of said rotor and the pistons 31 therewith will result in radial reciprocation of said pistons in the slots or displacement chambers 29, 30 due to the coacting cam action between the bands 25 and the end portions 35 of the pistons. If, on the other hand, the slide-pieces 22 are adjusted to dispose the bosses 24 and the bands 25 concentrically with respect to the shaft 26 and the rotor 28, rotation of said rotor and the pistons 31 will not result in any reciprocable movement of said pistons. It will be apparent, therefore, that the stroke of the pistons 31, between zero and maximum, is variable by vertical sliding adjustments of the slide-pieces 22 in their channels 21. Obviously, the bands 25 may be eliminated and the ends of the pistons 31 may directly engage the bosses 24. The bands 25 preferably are used, however, because they may readily be hardened to reduce wear and because they may readily be removed.

Formed in the casing 10 at opposite sides of the cylinder 11 in alignment with the openings 12 and 13 and opening into said cylinder 11, is a pair of circumferentially extending channels 36, 36 of any suitable width and depth the upper and lower ends of which, at the bottom and the top, respectively, of said cylinder 11, are spaced apart distances corresponding approximately to the widths of the pistons 31. Accordingly, assuming an eccentric relationship between the bands 25 and the rotor 28, it is manifest that, depending upon the direction of rotation of said rotor, the pistons 31 will move inwardly during their registration with one of the channels 36, thereby drawing fluid into the slots or displacement chambers 29, 30, and will move outwardly during their registration with the other of said channels 36, thereby forcing fluid from the slots or displacement chambers 29, 30. Thus, rotation of the

rotor 28 obviously will result in fluid being pumped from whichever may be the inlet to whichever may be the outlet of the openings 12, 13.

Bolted or otherwise suitably secured upon the top of the casing 10 is a housing 37, and in this housing and dividing the same into lower and upper pressure chambers 38 and 39, respectively, is a flexible diaphragm 40 to which is suitably secured a pair of arms 41, 41 which are suitably connected to the slide-pieces 22 as, for example, by means of screws, rods or other suitable connecting elements 42 which extend slidably through openings in the top wall of the casing 10. Thus, flexure of the diaphragm 40 is effective to produce vertical adjustments of the slide-pieces 22 and of the bosses 24 and the bands 25 carried thereby to vary the stroke of the pump pistons. In this connection it will be observed that a spring 43 is provided to act downwardly upon the diaphragm 40 and the arms 41 to tend constantly to urge the slide-pieces 22 to their limits of downward movement for maximum stroke of the pump pistons and that variations in the stroke of said pistons therefore is dependent upon the existence in the pressure chamber 38 of a pressure acting upwardly upon the diaphragm 40 with a force in excess of the force exerted downwardly upon said diaphragm by the spring 43.

It will further be observed in connection with the foregoing that in the top of the casing 10 is a pair of ducts 44, 44 which provide communication between the pressure chamber 38 and the upper ends of the channels 36, 36, respectively, and that a pivoted or flap type check valve 45 is capable of being pivoted to either of a pair of supports 46, 46 in the chamber 38 so as to cooperate with either of the ducts 44 to permit flow of fluid through the same into the pressure chamber 38 and to deny flow of fluid through the same from said pressure chamber. This check valve is pivoted to cooperate with the duct 44 which is related to the channel 36 at whatever may be the inlet side of the pump, depending upon the direction of rotation of the rotor 28. Accordingly, the chamber 38 is subjected to the pump outlet pressure of the fluid being pumped and if, for any reason, this pressure exerts a force upwardly upon the diaphragm 40 in excess of the spring pressure and any other pressure exerted downwardly thereon, said diaphragm will flex upwardly with consequent raising of the slide-pieces 22 and reduction in the stroke of the pump pistons commensurate with the difference in pressures above and below said diaphragm. Thus, not only the quantity of fluid pumped by the pump is controlled automatically in response to variations in the pressure of the pumped fluid at the outlet side of the pump, but the consequent tendency is to maintain a substantially constant or uniform pressure of the pumped fluid.

Preferably, but not necessarily, means is associated with the diaphragm 40 to render the same smoothly acting in operation, and this means may comprise, for example, a dash-pot consisting of a piston 47 suitably secured to said diaphragm and depending therefrom into a cylinder 47' formed in the upper wall of the casing 10, the said cylinder being in communication at its bottom with the chamber 38 through a small duct 48.

Conveniently, the arms 41 may be formed as integral parts of the piston 47. Conveniently, too, the housing 37 may be of two-part construction comprising lower and upper parts 49 and 50, respectively, between which the diaphragm 40 may be marginally clamped.

Preferably the piston 47 is bored from its top to accommodate the lower end portion of the spring 43 and preferably means is provided to vary the strength of said spring to determine the pressure of the pumped liquid required to reduce the stroke of the pump pistons 31.

While any suitable means may be provided for varying the strength of the spring 43, one suitable means for this purpose may comprise, as shown, an abutment disk 51 for the upper end of said spring keyed or otherwise mounted in a vertical bore 52 of the upper housing part 50 for non-rotatable, vertical sliding movement in said bore, and a screw 53 swiveled to said upper housing part and threaded through said disk. Thus, by rotatably adjusting said screw, said disk may be adjusted vertically to vary the strength of said spring 43. The screw 53 may have a flange 54 interposed between the top of an exteriorly threaded neck 55 at the top of the upper housing part and an inwardly extending flange 56 of a unit 57 threaded on said neck to provide a swiveled connection between said housing part and said screw, this arrangement being simple and having the advantage that by loosening the nut 57 the screw 53 may readily be rotated and that by tightening said nut, said screw may readily be fastened against rotation in any rotatably adjusted position thereof.

The shaft bearing opening in the plate 16 of the plug unit 15 is closed at its outer end and therefore there is no possibility of leakage of fluid from the pump around said shaft at this point. On the other hand, the shaft bearing opening in the plate 16 of the plug unit 14 extends entirely through said plate and therefore it is necessary to seal said opening against leakage of fluid from the pump therethrough. In this connection it will be observed that the pump casing 10 extends beyond the wall 18 and is closed at its outer end by a cap-piece 58 having therein a central bearing opening in which is journaled an extension 26' of the shaft 26 which at its inner end, has a suitable non-rotatable, longitudinally slideable connection with the adjacent end of the shaft 26, this connection being afforded, for example, by a tongue 59 on the end of the shaft 26 engaged in a slot in the end of the shaft extension 26'.

In an annular channel in the inner face of the cap-piece 58 in surrounding relationship to the shaft extension 26' is disposed a suitable gasket 60, while on the shaft extension 26' is an annular flange 61 which bears against the inner edge of said gasket. In addition, a cup member 62 is mounted on the shaft 26 with its closed end facing inwardly and bearing against an annular rib 63 on the outer face of the plate 16 and with its open end facing outwardly. In this cup member and surrounding the shaft 26 is a suitable gasket 64, while between said gasket and the flange 61 is interposed an expansion coil spring 65 which tends constantly to urge the shaft extension 26' outwardly and the gasket 64 and the cup member 62 inwardly. Since inward movement of the cup member 62 is limited by the plate 16, one effect of the spring 65 is to maintain the gasket 64 under compression in tightly sealing engagement with the shaft 26 and, at the same time, to maintain the inner face of the cap member 62 in tightly sealing engagement with the rib 63. The other effect of said spring 65 is to urge the shaft extension 26' outwardly, with the result that the flange 61 maintains the gasket 60 under compression in tightly sealing engagement with said shaft extension and with

the surrounding portion of the cap-piece 58. Thus, even though any fluid may leak from the cylinder 11 into the chamber 66 containing the spring 65 and the seals, any leakage of fluid from said chamber effectively is prevented.

The shaft extension 28' projects outwardly beyond the cap-piece 58 for connection with any suitable power unit for driving the pump, and openings 67 preferably are provided in the casing 10 for the supply of lubricant to the chamber 66 and for the drainage of said chamber.

Fig. 2 of the drawings illustrates a conventional fuel feeding system for an aircraft engine including a pump constructed in accordance with the invention. In Fig. 2 an internal combustion engine is indicated as A, a supercharger is indicated as B, a fuel tank is indicated as C, a power driven fuel pump constructed in accordance with the invention is indicated as D, and a hand-pump for use in the event of failure of the pump D or for engine starting or other purposes, is indicated as E.

A pipe a connects the fuel tank C with the inlet side of the hand-pump E, and at the inlet side of said hand-pump is a by-pass passageway b which is connected with the inlet side of the pump D by a pipe c. Another pipe e connects the outlet side of the hand-pump E with the inlet side of the pump D, and a pipe f connects the outlet side of the pump D with the engine A.

Ordinarily, the pump D functions to draw fuel from the tank C via the pipe a, the by-pass b and the pipe c and to deliver it to the engine via the pipe f in accordance with demand and under substantially constant or uniform pressure. At times, however, it may be necessary or desirable to employ the hand-pump E to deliver fuel to the engine, in which event the flow is via the pipe a to the inlet side of said hand-pump, from the outlet side thereof to the inlet side of the pump D via the pipe e, through the channel 36 and the duct 44 at the inlet side of said pump D, then into the chamber 36 past the check valve 45, through the duct 44 and the channel 36 at the outlet side of said pump D, and then to the engine via the pipe f.

The supercharger B is connected with the upper chamber 39 of the pump D by a pipe g. Therefore, said chamber 39 is subjected to supercharger pressure which acts downwardly upon the diaphragm 40 and augments the spring 43 in this respect. Consequently, variations in the stroke of the pistons 34 of the pump D is a function of the difference between the pressure of the fluid at the outlet side of said pump on the one hand, and the combined pressure of the spring 43 and the supercharger B on the other hand, in any instance where a supercharger or other pressure device is connected with the chamber 39. In this connection it is manifest that, for many purposes, the chamber 39 may

not be necessary and may be eliminated if desired.

From the foregoing description considered in connection with the accompanying drawings, it is believed that the construction and operation of the present pump will be clearly understood and its advantages appreciated. It is desired to point out, however, that while only a single, specific embodiment of the invention has been illustrated and described, the same is readily capable of embodiment in various other specifically different mechanical forms within its spirit and scope as defined in the appended claims.

15 I claim:

1. A variable capacity pump, comprising a housing defining a cylinder having inlet and outlet ports therein; a rotor in said cylinder, the peripheral surface of which is in continuous contact with the wall of said cylinder; longitudinal slots in the peripheral surface of said rotor; pistons radially movable in said slots and carried by said rotor successively past said inlet and outlet ports; means eccentric with respect to the longitudinal axis of said rotor providing a mount for said pistons whereby to impart a pulsating motion thereto so that fluid is drawn into said slots at said inlet port and expelled therefrom at the outlet port, the length of strokes of said pistons determining the rate of flow of fluid through the pump; operating fingers extending into said cylinder into cooperative relation with said piston mounts for shifting said mounts toward and from a position more nearly coaxial with said rotor to shorten and lengthen the strokes of said pistons; and fluid pressure operating means for controlling action of said operating fingers.

2. A variable capacity pump, comprising a housing defining a cylinder having inlet and outlet ports; a rotor in said cylinder movable about a fixed axis; a pair of diametrically opposed slots in said rotor; pistons in said slots connected for simultaneous operation, said pistons being movable transversely of the axis of said rotor and carried by said rotor successively past said inlet and outlet ports; a pair of cylindrical piston mounts at the opposite ends of said rotor and adjustable radially thereof toward and from positions coaxial with the rotor, the ends of said pistons being in sliding engagement with said cylindrical mounts and guided thereby through radial strokes which are variable in length in accordance with the position of the piston mounts with respect to the axis of the rotor; a single spring means pressing said piston mounts to positions effecting radial strokes of a maximum length of said pistons; and fluid pressure operating means opposing the action of said spring means.

MERLYN M. CULVER
